(57) **CLAIM**

The ornamental design for a rifle bolt as shown and described.

DESCRIPTION

FIG. 1 is a perspective view of a rifle bolt, showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is an enlarged view of the portion labeled FIG. 8 from FIG. 7; and,

FIG. 9 is an enlarged view of the portion labeled FIG. 9 from FIG. 1.

The evenly spaced broken lines depict portions of the rifle bolt that form no part of the claimed design. The dash-dot broken lines depict boundaries of the rifle bolt that form no part of the claimed design. The dash-dot broken line, forming a circle, in FIG. 1,7,8, & 9 depict the extent of the enlarged views and from no part of the claimed design.

1 Claim, 8 Drawing Sheets
